HARVESTER RAKE.

No. 278,850.

Patented June 5, 1883.

UNITED STATES PATENT OFFICE.

SAMUEL D. BATES, OF LEWISBURG, PENNSYLVANIA.

HARVESTER-RAKE.

SPECIFICATION forming part of Letters Patent No. 278,850, dated June 5, 1883.

Application filed November 7, 1882. (No model.)

To all whom it may concern:

Be it known that I, SAMUEL D. BATES, a citizen of the United States, residing at Lewisburg, in the county of Union and State of Pennsylvania, have invented certain new and useful Improvements in Harvester-Rakes, of which the following is a specification, reference being had therein to the accompanying drawings.

10 Figure 1 is an elevation of the raking mechanism from the grain side of the machine, partly in section, on line $y-y$, Fig. 4. Fig. 2 is a sectional view, showing the devices for tripping the switch of the rake-arms. Fig. 3 is a plan view of the cam-track. Fig. 4 is a top view of the raking mechanism and a portion of the rest of the machine. Fig. 5 is a front view, partly in section, on line $x-x$, Fig. 4. Fig. 6 is a perspective of the tripping mechanism.

15 In the drawings I have shown sufficient part of a harvesting-machine to illustrate the method of applying my improved raking and reeling mechanism, though it will be readily understood that the latter can be employed with machines more or less differing from what is shown. The power is transmitted from the drive-wheel by any suitable train of gearing. I prefer that shown in another application heretofore filed, of which this is a division.

20 The raking mechanism is supported in a tubular standard, L, fastened to the platform. In this standard is journaled a vertical shaft, carrying at the upper end a rake-head, M, and at or near its lower end a bevel-wheel, M'.

25 The rake-arms N are respectively hinged to the rotating head M. Said rake-arms may be of the kind shown in previous Patent No. 236,533, or of any preferred character. Each arm has on its hinge a downwardly-projecting stud, m, and roller m'. Camways for raising and lowering the rake-arms are supported upon the stationary tubular standard L, said 30 camways being substantially of the character shown and described in my aforesaid patent. The camway which serves to guide the arms when they are to operate as rakes to sweep the grain from the platform consists of an upper 35 part, O, describing an arc of a circle, and a lower part, O'. The way which serves to guide

the arms when they operate as reels consists of the part O, the pivoted cam or track O', a switch or cam-gate, P' P², and a short stationary cam, P¹, situated between the pivoted cam 55 O' and the switch P' P². The switch P' P² is formed in the shape of a bell-crank lever, with the pivot p on its under side mounted within a tubular bearing depending from the cam-way-support. The pivot o of the cam or track 60 O' is mounted in a tubular bearing, o'. The pivot p of the switch P' P² carries an eye, p', secured directly to the pivot p or to a plate or arm, p², attached to said pivot. p³ is a coiled spring, one end of which is connected 65 to the pivot p, the other end being attached to some stationary part. This spring p³ tends to force the forward arm, P', of the switch outwardly, and when said arm is at its outermost position the inner or rear arm, P², is situated across the inner camway. If one of the 70 arms n operates as a rake—that is to say, moves so as to carry its roller m' along the camway O'—it will strike against the rear arm, P², as it moves rearwardly, and will throw 75 said arm P² outwardly, thereby bringing inward the arm P', so as to close said camway O'. As soon as the arm P' reaches its innermost position it is locked there by means of a link, Q, pivoted to the arm p² by a pin, q, and 80 provided with a shoulder, s', which engages with a stationary shoulder, r, after the switch-arm has been thrown in. This shoulder r is upon a stationary bracket or pendant secured to the under side of the cam-support and consisting of a vertical grooved part, R, and a horizontal part, R', for fastening it in place. The vertical part R is provided with a longitudinal way or passage. In this way or passage there is placed the sliding tripper R². 85 90 This tripper is provided with a series of teeth, r', upon the rear side, and a series of teeth, r'', upon the front side.

S is a lever, pivoted at s in the lower end of the vertical part R of the bracket. The outer 95 or rear end, s'', of the lever is so situated that it can engage with cams S' upon the upper side of the bevel-wheel M', which cams successively throw the end of the lever up, it falling again after the cam passes from under the outer end. 100 S' is a dog, pivoted to the lever S and arranged to engage with the teeth r' on the tripper R².

When a cam, S', lifts up the lever S the dog S² engages with one of the teeth and thrusts the tripper R² up one step. After being thus lifted one step it is held by means of a spring-⁵ catch, T, which is provided with a dog, t, that engages successively with the teeth r² on the front side of the tripper R². The dog is forced inwardly by means of a coiled spring, t', at the lower end of the catch.

10 There is an aperture at r⁴ through the bracket, and the link Q passes through this aperture. When the arm P' of the switch is in its outermost position the link Q has its end thrust forward far enough to engage with the upper end ¹⁵ of the spring-catch T and force it forward, so as to hold the dog t out of engagement with the teeth r².

The operation of these parts last described is as follows: If it be desired to have every ²⁰ fourth rake-arm operate as a rake, the tripper R² is so adjusted that at the fourth upward movement of the lever S and dog S² the tripper shall lift the end of link Q to release the shoulder s' from the shoulder r. If, after ²⁵ the tripper is so adjusted, the machine be put into operation, it will be seen that as the wheel M' revolves, one of the cam S' will lift up the lever S, which, by its dog S², will lift up the tripper one step. As soon as the cam S' passes from ³⁰ the end of the lever S the latter drops, carrying the dog S² away from the teeth r'; but the tripper is prevented from falling by the dog t on the spring-catch T. The outer cam-track still remains open, and the next rake-arm will be thrown up away from the platform. When the second cam S' strikes the lever S the tripper is lifted another step and is held there by the spring-catch, the switch still remaining unaffected. The third cam S' ³⁵ operates in a similar manner to lift the tripper R². When the fourth cam engages with the lever to elevate the tripper the fourth step it (the tripper) has reached a point high enough to engage with the link Q, and it releases the shoulder s' from the shoulder r, whereupon the spring p³ throws the switch-arm P' outward and pushes the link Q through the aperture r⁴ far enough to thrust the spring-catch T outward. The thrusting of the spring-catch ⁴⁰ 50 outward drops the tripper to its lowermost position, after which it is ready for a similar series of operations. After the switch-arm P' is moved outward by the spring the inner cam-track is opened and the fourth reel-arm is carried down over the platform; but as soon as its roller M' strikes the arm P² of the switch it will swing the arm P' inward again, and thereby draw the link Q back away from the spring-catch T far enough to have the shoulder s' ⁵⁵ 60 again engage with the shoulder r, after which the device is set for another operation.

If it be desired to cause the raking of the platform at shorter intervals, this can be accomplished by preventing the tripper R² from falling to its lowest position. Preferably a series of apertures, r⁵, are formed in the bracket

R, through which apertures a pin, r⁶, can be passed and secured in the vertical path of the tripper, so as to stop the latter. The positions of these apertures r⁵ are so related to the positions of the teeth r' on the tripper that when the pin r⁶ is in the third aperture from the top, three of the "step-by-step" movements will move the tripper high enough to release the switch; when the pin is in the fourth hole, ⁷⁰ four of such movements will release it, and so on throughout the series in an obvious manner.

If the operator should at any time desire to delay the raking action, he can accomplish this by releasing the tripper R² before it reaches the link Q in its upward movement. One of the forms of mechanism whereby the operator can thus release the tripper I have shown in the drawings, it being constructed as follows: ⁸⁰ 85

U represents a rock-shaft mounted in bearings on the draft-frame. It is provided with a foot-crank, U', in front of the operator's seat, and a crank-arm, u, at the inner end.

V is a swinging lever, pivoted at its upper end to the bracket R or to the cam-support, and at its lower end pivoted to a link, V', which in turn is pivoted to the crank-arm u.

v is a laterally-projecting pin carried by the swinging lever and arranged to press against the lower end of the spring-catch T when the lower end of the lever V is moved backward. The lower end of said lever is thus moved backward by the operator by pressing his foot upon the crank U'. The pin v swings the upper end of the catch T out far enough to release the dog t from the teeth r² of the tripper. In this way the operator, while in his seat, can regulate with ease the size of the bundles which are to be delivered from the platform. ⁹⁵ 100 105

The swinging lever V is held in the proper position relatively to the spring-catch T by means of two coiled springs, V² V³, carried by a loosely-mounted arm, V⁴, said springs engaging with the opposite sides of an arm, V⁶, formed with or attached to the lever V. ¹¹⁰

With a mechanism of this sort I obviate entirely the necessity of the complicated devices which have heretofore been used for regulating the raking of the platform, and provide a simple means for varying the interval between the successive operations of raking.

Heretofore it has been necessary to remove one or more parts and replace them by others in order to effect a variation in this respect. ¹²⁰ By having a rising and falling tripper the fall of which can be regulated by a pin or equivalent means, I provide a much simpler and more accurate and durable mechanism than those heretofore used with which I am acquainted. ¹²⁵

By means of the following devices the operator can cause the raking of the platform at any time—that is, by means of the next cam S'.

V⁸ is an arm pivoted to the link Q and hanging downward. Its lower end is adapted to be swung forward, so as to rest upon the surface s⁶, formed in the dog S². This arm V⁸ can

be thus swung forward by the operator by means of the rock-shaft U, treadle U', link V' and lever V, arm V⁶, and the part S⁵, projecting laterally from the arm V⁶. The proper movement is effected by turning the foot-crank U' forward, which results in having the part S⁵ moved forward, and it swings forward the arm V⁶ until its lower end rests upon the aforesaid surface s⁶ on dog S². After the arm V⁶ is engaged with the dog S² it will be seen that a single rising of the lever S will throw up the link Q far enough to disengage its shoulder s' from shoulder r, and thus open the switch. I am aware that switch-trippers have been heretofore used adapted to unlock a shoul- 15 dered latch, and in combination therewith means for imparting a step-by-step movement in circular paths to means for operating the trip, and I do not claim such devices as my in- 20 vention; but there are many advantages inci- 25 dent to a construction of the character of mine which are not to those which have been heretofore used. By employing a rectilinearly-mov- 30 ing trip mounted loosely in a guide I avoid the necessity of springs and the other returning de- 35 vices that have been heretofore used, which are liable to get out of working order, and can be repaired only with serious difficulty and incon- 40 venience. In my case, the tripper being loosely mounted and allowed to return by its own gravity, it need not be permanently connected with the other parts, and no serious disarranging of it or stopping of its operations is possible under ordinary circumstances. In all the ordinary 45 positions of the machine it will operate with uniformity to a greater extent than is the case with those in which the trip is carried by the swinging arm or is arranged to oscillate about an axial line.

40 What I claim is—

1. In a raking and reeling mechanism, the combination, with the switch-opening device and the lock, of the switch-tripper mounted loosely in a guideway, whereby it is adapted 45 to rise and fall in a straight line, substantially as set forth.

2. The combination of the switch, switch- 50 locking devices, the switch-opening device, means having a step-by-step movement to put into operation the switch-opening device, means independent of the step-by-step move- 55 ment to cause an immediate operation of the switch-opening device, a lever constructed and arranged substantially as set forth, and means by which said lever is caused to engage with the means having the step-by-step movement to open the switch or with those which open it immediately, as desired.

3. The combination of the switch, switch- 60 locking devices, a switch-opening device, means having a step-by-step movement to put into operation the switch-opening device, means which cause an immediate operation of the switch-opening device independently of the 65 step-by-step movement, and devices under the control of the operator which, when moved in

one direction, engage with the means having the step-by-step movement, and when moved in an opposite direction engage with the means which immediately open the switch, substantially as set forth. 70

4. The combination of the switch, the switch-lock, a rectilinearly rising and falling switch-tripper, a vibrating dog which intermittently engages with the trip, another dog which engages with said trip to hold it, the spring which holds the last said dog in engagement with the trip, and means under the control of the driver for disengaging the last said dog to release said trip, substantially as set forth. 75

5. In a raking and reeling apparatus, the combination of the switch, the switch-lock, the rake-shaft, the rectilinearly rising and falling switch-tripper, a dog intermittently en- 80 gaging with the tripper, means operated by 85 the shaft which vibrate said dog, a spring-dog which engages also with the tripper, and means under the control of the driver for disengag- 90 ing the last said dog to release the trip, the said trip being arranged, substantially as set forth, to return to its initial position after the releasing of the dog.

6. The combination of the switch, the switch-locking devices, the switch-opening device, the tripper mounted loosely in a straight guide- 95 way, the device which intermittently engages with said loose tripper to impart a step-by-step movement thereto in a right line, and retaining devices adapted to be in direct engagement with the tripper permanently until it unlocks 100 the switch, substantially as set forth.

7. The combination of the switch, the switch-opening device, the switch-lock, the rectilinearly-moving tripper mounted loosely in a guideway and the pin adapted to be placed across 105 the guideway to limit the movements of the tripper, substantially as set forth.

8. The combination of the switch, the latch Q, the arm V⁶, loosely pivoted to the latch, the intermittently rising and falling dog S, and the 110 device controlled by the driver for swinging the arm V⁶ into position to engage with the dog S when it rises to cause an immediate unlatching of the switch, substantially as set forth.

9. The combination of the switch, the latch 115 Q, pivoted thereto, the dog-lever T, the end of which lies across the path of the latch after the same is disengaged, the tripper R², the spring t', the dog S, and the pivoted lever V under the control of the driver and adapted 120 to engage with the dog-lever T, substantially as set forth.

10. The combination of the switch, the switch- 125 latch, the tripper R², the means for stopping the advance of the tripper, means for imme- diately lifting the latch, and the pivoted lever V, provided with the arm V⁶ to bring into ac- 130 tion the devices which immediately open the switch, and an arm, v, to release the tripper, substantially as set forth.

11. The combination, with the switch-un- 130 locking device, of the lever V, a rod, V⁴, and

the springs V² V³, which normally hold the lever out of engagement with the switch-unlocking devices, substantially as set forth.

12. The combination, with the rectilineally rising and falling tripper provided with ratchet-teeth, of the vibrating dog S, engaging with said tripper to advance it, and the dog t, which under a yielding pressure also engages

with said tripper to hold it in an advanced position, substantially as set forth.

In testimony whereof I affix my signature in presence of two witnesses.

SAMUEL D. BATES.
